EDWARD J. STRIEBLE, OF MILES CITY, MONTANA.

STUMP BURNER

Application filed February 10, 1930. Serial No. 427,329.

This invention relates to stump burners and has for an object the provision of means for quickly and economically destroying stumps.

5 To this end, the invention includes a casing adapted to be positioned over a stump and supplied with liquid fuel under pressure, with means to regulate the supply of fuel, means to provide and regulate down draft 10 for the casing, and means to regulate the draft outlet, both at the top and bottom of the casing to provide perfect combustion therein and destroying a stump within a very 15 short time and with a minimum consumption of fuel.

With the above and other objects in view, the invention further includes the following novel features and details of construction, to be hereinafter more fully described, illustrated in the accompanying drawings and 20 pointed out in the appended claims.

In the drawings:

Figure 1 is an elevation illustrating the invention.

25 Figure 2 is a top plan view of the burner casing.

Figure 3 is a section on the line 3—3 of the Figure 2.

30 Figures 4 and 5 are sections taken respectively on the lines 4—4 and 5—5 of Figure 3.

Figure 6 is an enlarged fragmentary sectional view at the juncture of the oil and air supply pipes.

35 Referring to the drawings in detail, where in like characters of reference denote corresponding parts, the reference character 10 indicates the burner casing, which is made of suitable metal, open at the bottom and provided with a closed top 11. The casing 10 is provided with a slide door 12 thru which extends a pipe 13, and connected to the inner end of this pipe is an arcuate burner 14.

40 The pipe 13 communicates with the bottom of a fuel tank 15 which is adapted to contain oil and air under pressure, the latter being supplied from a suitable source from a pipe 16. Oil is introduced into the tank thru a filling nipple 17, and the tank

may be supported upon a suitable structure 18. A valve 19 controls a discharge of oil from the tank.

Extending from the top of the tank is an air supply pipe 20, thru which air under 45 pressure is supplied to the pipe 19 from the tank 15, the supply being regulated by a valve 21. Located within the pipe 13 at its juncture with the pipe 20 is an ejector nozzle 22, so that air passing from the pipe 20 to the pipe 13 will draw oil thru this nozzle and force the same under pressure from the pipe 13 to the burner 14, so that a supply of oil and air is furnished to the burner. The burner is initially heated so that the oil will 50 be vaporized and a gaseous mixture will form which will result in a hot flame. As the burner 14 is of arcuate shape, it will partly surround the stump "S" so that the stump will be quickly consumed. The stump is 55 preferably bored, as indicated at 23 to permit of the passage of flame therethru and materially reduce time necessary for burning.

The casing 10 is provided with slide doors 24, which may be adjusted to regulate the entrance of air, while a pipe or flue 25 communicates with the casing at the top and bottom thereof, as indicated at 26. This communication is controlled by a means of slide dampers 27. The dampers may be adjusted 60 to close or partly close communication either at the top or bottom of the casing.

Extending downward thru the top of the casing are down draft pipes 28. These pipes are open at the bottom and terminated short of the bottom of the casing, while their upper ends are provided with dampers 29 by means of which the passage of air thru the pipes may be regulated.

65 The pipes 28 are vertically adjusted thru the medium of adjusting collars 30, so that by regulating the height of these pipes, down draft through the casings may be accordingly controlled and perfect combustion provided for the burner.

The invention is susceptible of various changes in its form, proportions and minor details of construction, and the right is herein reserved to make such changes as prob- 100

ably fall within the scope of the appended claims.

Having described the invention what is claimed is:

- 5 1. In a stump burner, a casing closed at the top and adapted to be placed over the stump to be burned, a burner within the casing, means to supply fuel to the burner, an outlet flue communicating with the casing at the top and bottom of the latter, and dampers to control such communication and regulate the draft from the top and bottom of said casing.
- 10 2. In a stump burner, a casing closed at the top and adapted to be placed over the stump to be burned, a burner within the casing, means to supply fuel to the burner, an outlet flue communicating with the casing at the top and bottom of the latter, dampers to control such communication and regulate the draft from the top and bottom of said casing, a down draft pipe extending thru the top of the casing and terminating short of the bottom thereof, a damper to control the upper end of the pipe, and means to adjust the pipe vertically to regulate such draft.
- 15 3. In a stump burner, a casing closed at the top and adapted to be placed over the stump to be burned, a burner within the casing, means to supply fuel to the burner, an outlet flue communicating with the casing at the top and bottom of the latter, dampers to control such communication and regulate the drafting from the top and bottom of said casing, down draft pipes extending thru the top of the casing and terminating short of the bottom thereof, dampers to close the upper ends of the pipes, a means to adjust the pipes vertically to regulate such draft.
- 20 4. In testimony whereof I affix my signature.
- 25 EDWARD J. STRIEBLE.
